Geo. S. Borelli

ATTORNEY

UNITED STATES PATENT OFFICE.

LOUIS BOSELLI, OF NEW YORK, N. Y.

SPARK-PLUG INDICATOR AND INTENSIFIER.

Application filed October 12, 1923. Serial No. 668,080.

To all whom it may concern:

Be it known that I, LOUIS BOSELLI, a citizen of the United States, residing at New York city, borough of Manhattan, in the county of New York and State of New York, have invented certain new and useful Improvements in Spark-Plug Indicators and Intensifiers, of which the following is a specification.

10 This invention relates to ignition devices and has particular reference to spark plug attachments for use especially in connection with internal combustion engines.

Among the objects of the invention is to 15 provide mechanism located preferably within easy reach and view of the driver of an automobile or the like and electrically connected with the several spark plugs of the motor and adapted to serve first, as an indicator of the condition of the spark plugs, and secondly, as a means for intensifying 20 the spark so as to remedy in most cases the faulty action of the plugs within the engine cylinders.

25 More specifically, the means employed by me in my practice and substantially as illustrated herein comprises an indicator plate or the like located on the instrument board of the automobile and having a series of windows pertaining respectively to the spark plugs and having associated with the windows spark gap connections with all of which is associated a common ground connection manually operated so as to enable 30 the driver on the manipulation of the ground connection to locate and correct faulty spark plugs.

With the foregoing and other objects in 40 view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

50 Figure 1 is a face view of the instrument board attachment.

Fig. 2 is a rear view of the same mechanism as in Fig. 1 and having a diagram of the wiring.

55 Fig. 3 is a sectional view on the line 3—3 of Fig. 1.

Fig. 4 is an enlarged detail view of one of the spark gap screws.

Referring now more specifically to the drawings I show at 10 a disk or plate of insulation fitted in or through, in any convenient manner, the instrument board 11 and held in place by means of a flanged rim 12 between the face of which and the face of the disk is located a transparent window 13. This disk 10 is shown provided for four 60 spark gaps for four plugs, but it will be understood that for an engine having a greater number of cylinders the device will be correspondingly designed. To this end I show a circular series of four pits 1, 2, 3, and 4, pertaining to the respective spark plugs, said pits being formed by drilling inward from the face of the disk toward the back thereof and preferably equally distanced from the center of the disk. In the center of the disk 65 is formed a smooth hole 14 counterbored and tapped at the front end and also tapped at the rear end.

70 15 indicates a metallic thimble projected through the center of the glass plate 13 and 75 tapped into the counterbore of the central hole 14. A plunger 16 is fitted slidably in the thimble having a manually operatable head at the front end and having a smooth rear end fitted in the hole 14. A spring 17 80 surrounding the plunger and bearing at one end against the head of the thimble and at its other end against a shoulder 18, tends to 85 hold the plunger forward so that its rear end is spaced from a contact screw 19 fitted 90 adjustably in the tapped rear end of the hole 14 and locked by suitable lock nuts 20. A ground connection 21 is attached to this 95 screw 19. The normal gap between the plunger and the screw 19 is adapted to be closed by pressing forward upon the plunger.

22 indicates a series of radial screws projected transversely or radially across the pits and tightened against the surface of the thimble, serving thereby to lock the thimble in place and to make a common connection or contact between the thimble and parts therein and said screws. These screws for the sake of best action of the device 100 have pointed heads each having a pair of kerfs 23 on opposite sides of its point for the application of a spanner screw driver which being projected through a hole 24 at the periphery of the disk will provide for 105 110

the tightening or removal of the screws 22. While in operation the pointed heads of the screws lie within the pits.

25 indicates a series of outer screws fitted 5 adjustably in the holes 24 and having pointed inner ends suitably spaced from the pointed heads of the screws 22, making suitable spark gaps which in practice are so regulated as to be somewhat wider than the 10 normal gaps between the sparking points of the plugs.

Each screw 25 after being adjusted is locked in place by means of a rearwardly projected screw 26 abutting directly against 15 it and locked in place in turn by nuts 27. Wires 1' to 4' are secured to the binding screws 27 by thumb nuts 28 and lead thence to the respective spark plugs as indicated by the diagrams. The screws 22 are preferably smaller than the screws 25 so that 20 they may be slipped directly through the holes 24 during assemblage.

The operation of the device, in view of the foregoing description, may be summarized 25 briefly as follows: The indicator disk as in Fig. 1 will always be in plain view of the operator or driver, and during the normal proper operation of the engine and spark plugs no substantial manifestation will be 30 noticeable at the several windows, the gap at each plug being less than in the window pertaining thereto, the spark will be produced at the proper place and will not be visible at the indicator. Moreover, the gap 35 at the rear end of the plunger is so great that no ground connection ordinarily is made. When, however, the driver has reason to suspect faulty spark plugs in his engine he will depress the plunger, closing 40 the gap between the plunger and the ground connection screw 19, thus bringing all the screws 22 into ground connection. In most instances if a spark plug is failing because 45 it is foul an intensified spark will be produced and be visible in its corresponding window at the indicator, so that the operator

while holding the plunger depressed can discover immediately which plug if any is failing, and, moreover, by holding the plunger depressed for a few moments the intensification of the charge through the indicator and sparking mechanism will serve to purge the foul plug contacts and so restore such plug to active operation again. This latter fact is evidenced by the discontinuance or failure of the spark at the window. When this result is obtained the driver naturally will release the plunger and proceed as at first with the engine in proper operation.

I am aware that it has been proposed heretofore to provide indicating devices for spark plugs having somewhat the same general operation as my improvement, but so far as I have been advised my construction 70 is far simpler and cheaper in construction and more reliable in operation than previous devices.

I claim:

In indicator mechanism of the class set 75 forth, the combination of a body of insulation having a central hole, the front end of which is counter sunk, a thimble fitted into the counter sink, a manually operated plunger fitted in the thimble and slidable rearward toward the rear end of the central hole, a spring acting upon the plunger holding it forward, a ground screw connection spaced normally from the plunger at the rear end of the central hole but adapted to 80 be engaged by the plunger when depressed, a series of screws fitted radially toward and against a thimble serving to lock the thimble in place, a corresponding series of outside screws in radial alignment respectively with the screws first mentioned and normally spaced therefrom forming spark gaps, and a series of combined locking means for the 85 last mentioned outside screws and connections for spark plug wires.

In testimony whereof I affix my signature.

LOUIS BOSELLI.
